ROTARY THROTTLE BLADE DESIGN

John S. Jaquith, Caldwell, N. J., assignor to Ben-
dix Aviation Corporation, Teterboro, N. J., a
corporation of Delaware

Application July 29, 1949, Serial No. 107,490

2 Claims. (Cl. 253—78)

1

The present invention relates to throttles for rotary turbines, and more specifically to the contour and design of the throttle blades.

The invention finds particular utility in high velocity aircraft and in accessories therefor, such as ram air driven power supplies, for example, where it is desired to throttle and control the ram flow propelling a rotor.

In installations of the type where a plurality of circularly disposed fixed vanes guide a ram air stream against the buckets of a turbine wheel to turn said wheel, and a rotary throttle is actuated by a motor to control the ingress of said stream to said vanes, for example, the design of the contour of the throttle blades is of paramount importance, for these are subject to sudden, and often, unpredictable load reversals, high frictional drag, compressibility effects, shock wave loads, and other aerodynamic disturbances characteristic of transonic and supersonic speed.

In conventional rotary throttling valves, the blades thereof are usually in the form of triangular prisms, i. e., in cross section the blade is substantially triangular in form having a base portion adjacent the nozzle block and sides that converge inwardly toward each other to meet at the apex of the triangle. Thus, the blade is provided with a relatively sharp edge that splits or divides the incoming airstream and causes it to flow over the side surfaces of the blades.

When the throttle valve is in open position the air stream passes from the side surfaces of the blade into the throat of the nozzles, i. e., the spaces between the stators of the nozzle block. Since the area of the throat of the nozzles is substantially less than the area defined between two adjacent apices of the blades, it is apparent that as the airstream enters the throat its velocity is increased with a result that the pressure of the airstream decreases. This phenomena is referred to in the art as "Bernoulli effect."

In instances where the stators of the nozzle block defining the nozzles are symmetrically disposed about an axis parallel to the airstream, in the open position of the throttle, the airstream splits or divides and passes into the nozzle throat without materially affecting the blades of the throttle. However, it has been found that where the stators are unsymmetrical so as to define curved or sinuous nozzles, the pressure of the air stream acting on the sloping sides of the blade are unequal and therefore produce an unbalanced force tending to rotate the throttle.

Moreover, it has been found heretofore that in the operation of a device of the above-indi-

2

cated character, as the motor actuates the throttle from full open to full closed position, the load due to Bernoulli effect will in some instances suddenly reverse itself in some intermediate position proximate to the two-third open position, thereby causing instability at the point of reversal and irregularity of the throttle operation, and necessitating a driving system free of backlash, and accordingly, more complicated and expensive, to overcome this condition.

It is, therefore, one of the objects of the present invention to provide a novel type of throttle blade wherein the foregoing disadvantages are substantially eliminated and to do so by novel and effective means.

Another object of the invention is to provide a novel type blade for a rotary ram air throttle, and upon which the throttle load due to Bernoulli effect will be reduced to a minimum.

Still another object of the invention is to provide a blade for a rotary ram air throttle free of instability due to the reversing of the load thereon by maintaining the load always in one direction.

Still another object of the invention is to provide a novel type of throttle blade for a rotary ram air throttle which will permit the throttle to be actuated by relatively lighter and lower-powered driving means.

The foregoing and other objects and advantages will appear more fully hereinafter from a consideration of the detailed description which follows, taken together with the accompanying drawings, wherein one embodiment of the invention is illustrated by way of example. It is to be expressly understood, however, that the drawings are for the purpose of illustration only, and are not to be construed as defining the limits of the invention.

Referring to the drawing wherein like reference characters designate like parts,

Figure 1 shows a front view of a rotary throttle.

Figure 2 is a section through one of the blades along the line 2—2 of Fig. 1.

Figure 3 is a schematic drawing showing the throttle blades in operating relation to the vanes and to the turbine wheel.

Referring now to the drawings and more particularly to Figures 1 and 3, a rotary throttle, generally indicated by the figure 10 comprises a series of blades 12 adapted by rotary motion to close the nozzle openings 14 of the nozzle block 16, which directs a ram air stream, indicated by the arrows "S," to the buckets 18 of a turbine wheel 20, as indicated schematically in Figure 3.

As shown in Fig. 2, the blades are substantially in the form of a triangular prism having a base portion 19 that is designed to close the nozzle spaces 14 in the block 16 and an apex or edge 22 that is adapted to project into and split the air stream "S" so as to pass it over the sloping sides 24 and 26 of the blade 12. The side 24 of the blade 12 is so contoured that adjacent the base 19 it merges or blends into the base 19 to form a knife-like edge 23. On the other hand, the side 26 of the blade 12 terminates short of the base 19 in a step 30 to the end that a flat surface 31 normally disposed to the base 19 is provided. Since this edge 30 of the blade 12 cuts across the air stream entering the throat 21 during rotation 15 of the valve in a closing direction, it is usually termed the leading edge of the blade. Thus, the blade 12 is provided at one edge of the base thereof with a flat surface 31 that is exposed to the pressure of the airstream flowing through 20 throat 21, while the opposed edge of the base is provided with a relatively sharp knife-like edge 28 that is exposed to the pressure of the air-stream flowing through the next adjacent throat 21. Since the flat surface 31 is normal to the air-stream, it is apparent the "Bernoulli effect" thereon will be greater than the "Bernoulli effect" on the knife-like edge 28, and thus a regulating load is placed on the blade 12.

As the blades 12 move from fully open position in the direction of the arrow A, the air stream strikes the tips of apices 22 of the blades and separates on either side of the blade 12, thereby creating a pressure distribution over the side surface 24 and the knife-like edge 28 on one side of 30 the blade 12 and the side surface 26 and flat surface 31 on the other side of the blade 12.

In normal operation with the throttle partially closed as shown in Figure 3, the velocity of the air stream "S" across the narrow throat 21 is 40 relatively higher than the velocity across the remainder of face 26 and face 24. This effect causes the force on face 26 to be lower than the force on the corresponding portion of the sloping surface on the opposing side 24. The net component force on face 24 will thereby tend to further close the throttle.

It will now be apparent to those skilled in the art that as the stream "S" passes over the blades 12, the pressure will always be greater on the surface 24 containing a knife-like trailing edge, since said edge will present only a small area for Bernoulli effect to act upon. The leading edge 30 is of sufficient thickness so that the load, during movements of the throttle from open to closed position, will always over-balance Bernoulli effect in the opposite direction.

It is further apparent that by regulating the height 32 of the step 30, the differential in pressure on the surfaces 24 and 26 may be further regulated and controlled.

In this manner, the throttle is susceptible of being driven by far less powered driving means than would ordinarily be employed without regulating the Bernoulli effect to aid the driving means. The step 30 in the leading edge of the blade negates the possibility that the load on the blade, due to Bernoulli effect, will reverse itself while the blade is in an intermediate position between full open and full closed throttle. This regulation of the load uni-directionally results in a more stable and smoother throttle operation.

There are thus provided means for regulating the action of the Bernoulli effect over the blades

of a rotary throttle controlling a ram air stream which are positive and reliable in operation, which improve the performance of the remaining components of the turbine, and which are simple and economical to manufacture.

While only one embodiment and one application of the invention has been illustrated and described, other changes and modifications of the form and relative arrangement of parts, which will now be apparent to those skilled in the art, may be made without departing from the spirit and scope of the invention.

What is claimed is:

1. In the combination of a plurality of fixed, spaced stators defining sinuous inlet nozzles therebetween to receive and direct an airstream to a turbine wheel and a rotary throttle valve having a plurality of spaced blades, each blade being individual to and coacting with one stator and the inlet nozzle defined by that stator and the next adjacent stator in the direction of rotation of the turbine wheel, each blade effective on rotation of the throttle valve relative to the stator to move relative to its coacting inlet nozzle to vary the effective area thereof, an improved blade for the rotary throttle valve, said blade comprising a substantially prismatic body having a base adjacent its coacting stator and inlet nozzle and a relatively sharp apex extending into the air-stream, the sloping surface between the apex and one side of the base terminating short of the base in a step having a first flat surface normal to the base and a second flat surface between the first flat surface and the sloping surface and parallel to the base and the sloping surface between the apex and the other side of the base merging into the base to form a knife-like edge with the base.

2. In the combination of a plurality of fixed, spaced stators defining sinuous inlet nozzles therebetween to receive and direct an airstream to a turbine wheel and a rotary throttle valve having a plurality of spaced blades, each blade being individual to and coacting with one stator and the inlet nozzle defined by that stator and the next adjacent stator in the direction of rotation of the turbine wheel, each blade effective on rotation of the throttle valve relative to the stator to move relative to its coacting inlet nozzle to vary the effective area thereof, an improved blade for the rotary throttle valve, comprising a body substantially triangular in cross section and having the base thereof adjacent its coacting stator and inlet nozzle, a step formed on said body at one end of the base and having a first flat surface extending forwardly from and normal to the base and a second flat surface extending normally from the first flat surface toward the opposite end of the base and parallel thereto, a knife-like edge formed on said body at the opposite end of the base, and side surfaces extending forwardly from the second flat surface of said step and said knife-like edge and converging toward each other to meet and form a relative sharp-edge for said body, said step forming the leading edge of said blade when said blade moves across the inlet nozzle to decrease the effective area thereof.

JOHN S. JAQUITH.
